Primary Examiner — Michelle E. Wilson*Assistant Examiner* — Richard E Yenchesky(74) *Attorney, Agent, or Firm* — W&K IP(57) **CLAIM**

The ornamental design for a hand-held garment steamer, as shown and described.

DESCRIPTION

FIG. 1 is a perspective view of the hand-held garment steamer showing my new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view.
